[57] ABSTRACT

An improved miniature size electric lamp is disclosed wherein an outer wire lead of the lamp is flattened and adhesively bonded to the inside rim of the base shell with an electrically-conducting basing cement. A method of manufacture for said lamp construction is also disclosed wherein the flattened section of the wire lead is aligned to lie in a plane approximately tangent to the envelope wall of the lamp prior to positioning the lamp envelope for assembly to the base shell. The particular lamp construction further can utilize an electrically-insulating basing cement to adhesively bond the lamp envelope to the base shell having the same resin binder as employed in the electrically-conducting basing cement so that both cements can be heat-cured simultaneously during a single operation in conventional automatic lamp manufacturing equipment.

MINIATURE LAMP CONSTRUCTION AND METHOD OF MANUFACTURE

BACKGROUND OF THE INVENTION

This invention relates, in general, to the manufacture of miniature size electric lamps which can be carried out simply and reliably with available automatic lamp manufacturing equipment. More particularly, the present invention deals with improved means to provide an electrical termination between the side-lead wire of a miniature lamp construction and the inner-surface of the lamp base.

Certain types of miniature size electric incandescent lamps, such as that commercially designated as the No. 327 sub-miniature lamp, are in general use at present for indicator and instrument lighting applications. Such lamps are customarily comprised of a tubular glass lamp bulb or envelope of very small size, e.g., around 7/32 inch diameter, on one end of which is mounted, axially of the bulb, a lamp base in the form of a metal shell of slightly larger diameter than that of the bulb and flanged at its closed end so that the lamp can be inserted and pushed bulb end first into a lamp socket in an instrument or other socket-supporting panel. The bulb contains a filament connected across a pair of current lead-in wires which are hermetically sealed through the side wall of the bulb at the neck end thereof by a conventional butt-type seal. The seal or neck end of the bulb extends into an open end of and is secured to the base shell by a customary ring of lamp basing cement which is peripherally disposed around the inside wall of the base shell below the rim, and the wire leads are electrically connected to the metal shell and end contact, respectively of the lamp base. The open inner end of the base shell into which the bulb extends is formed with an inwardly rolled or inturned curved lip within which the bulb is snugly received to center it in place more or less axially of the base shell.

The earliest method of electrically connecting the side lead of an electrical lamp to the base shell was to position the wire lead so as to extend out between the wall of the lamp bulb and the rim of the base shell when the base was placed in mounting position on the neck end of the bulb, and to then solder the wire lead to the outer side of the base shell adjacent its rim. Such procedure, however, resulted in a formation of a small mound or accumulation of the solder used for connection on the outer side of the base shell and protruding therefrom. For the intended usage of the particular subminiature indicator type lamps referred to above designed for bulb end first slide-in insertion of the lamp into the lamp socket, such protruding solder accumulations on the base shells would not be permissible since they would, in effect, block the endwise sliding insertion movement of the lamp into its socket. Accordingly, some other way of basing these type lamps had to be developed which would avoid the presence of any solder protrusions on the base shells.

To this end, the basing procedure now in customary use comprises the steps of forming the base shell with an apertured inward indent or recess in its side wall near the closed outer end of the base through the aperture of which indent the side lead is threaded and cut off flush with the outer side of the base shell, after which the cut-off lead is then soldered to the base shell within the indent. With this modified basing procedure,

the solder accumulation at the wire-to-base shell solder connection is concealed entirely within the indent in the base shell and thus does not protrude from the outer side thereof. However, because of the necessity for threading the side wire lead through the side aperture in the base shell, such a modified basing procedure precludes any use of conventional type automatic base threading mechanisms similar to that disclosed in U.S. Pat. No. 2,120,877 Uber, for example, which are customarily employed in the lamp making art, because of the substantial cost saving realized therefrom, to automatically feed and position lamp bases in mounting position on the glass bulbs of electric lamps, with the end or center contact wire lead of the lamp bulb extending through the customary end contact eyelet of the base in position for soldering thereto. In their customary manner of operation, these automatic base-threading mechanisms lower the bases down over and guide the upstanding center contact wire lead, extending endwise from the lamp bulb, into and upwardly through the opening in the end contact eyelet of the base. Obviously, the presence of a side wire lead extending laterally from the lamp bulb and required to be threaded into a side aperture in the base shell of the lamp, as in the case of the modified lamp basing procedure referred to above, would interfere with the lowering movement of the lamp base shell, by such automatic base-threading mechanisms, down over the upstanding center wire lead of the lamp and into mounting position on the end of the lamp bulb.

It has more recently been discovered in the manufacture of the larger size electrical lamps that the side lead can be soldered directly to the inside surface of the lamp base shell at its rim. In this newer method, a portion of the side lead is flattened after which a quantity of solder is coated on the flattened lead in portion, a flux applied over the solder and then the lamp envelope is forcibly inserted into the base shell which mechanically wedges the side lead between the shell and the bulb neck. After the lamp envelope has been assembled in this manner to the base shell, the rim of the base shell is heated to melt the solder coating on the wire lead section and form a solder connection thereof to the base shell. Such a method is not particularly adapted to the high speed lamp manufacturing machines presently employed for miniature lamp construction by reason of the physical interference which takes place between the protruding side lead and the base shell that would either cause misalignment of the parts being assembled or remove solder from the side lead and produce a poor electrical termination.

Many types of basing cements are also known to join a metal base to the glass envelope of an electric lamp. The original basing cements were electrically non-conductive and comprised of an inert filler material, an insulating binder, and a processing agent or vehicle. The typical binders were organic polymers which included shellac, phenol-aldehyde resins, silicone resins, and epoxy resins. More recently, it has been learned that conductive particulates, generally in the form of finely-divided metal powders, could be admixed to an otherwise electrically-insulating cement and render the entire composition electrically-conductive for some lamp applications. A known lamp construction comprises a hermetically sealed glass envelope from which a pair of lead-in wires protrude, wherein the lead-in wires are adhesively bonded to the glass envelope by a

conductive epoxy cement to separate metal tangs forming the lamp circuit with a resistance filament connected between the lead-in wires.

CROSS-REFERENCE TO RELATED APPLICATIONS

A newly discovered method of effecting electrical connection between the side lead wire and the inner-surface of the lamp base shell is disclosed in copending application, Ser. No. 197,662, filed Nov. 11, 1971, in the name of Steve Boros, which is entitled "METHOD OF BASING ELECTRICAL DEVICES", and which is now issued U.S. Pat. No. 3,785,020. In this method, the protruding end of the side lead is also flattened and coated with solder prior to insertion of the lamp envelope into the base shell. As distinct from the earlier discovered method of effecting an electrical connection between said flattened side lead and the inner-surface of the lamp base shell which have been reported above, the flattened wire lead section is further aligned prior to insertion of the lamp envelope into the base shell so that it lies in a plane approximately tangent to the envelope wall and thereby avoids interfering with placement of the lamp envelope in the base shell. Consequently, the lamp basing method according to said copending application, readily lends itself to the use of available automatic lamp manufacturing equipment being substantially free of the problems caused by misalignment between the lamp envelope and base shell or poorly soldered electrical connection between the side lead and the base shell.

Another copending application which is also assigned to the assignee of the present invention describes and claims a basing cement of the dual-purpose type for bonding a side lead to the base shell in an electric lamp as well as bonding the lamp envelope to the base shell. More particularly, in pending application, Ser. No. 320,531, filed Jan. 2, 1973 in the name of Mary S. Jaffe and entitled "LAMP BASING CEMENT," there is disclosed a lamp basing cement composition having an adhesive binder which comprises the heat-cured product of a 1,2-butadiene prepolymer, a vinyl type crosslinker and a free-radical initiator. A particulate filler is also included in the cement which determines if the heat-cured product will be insulative or electrically conductive. Either type cement can be cured during high speed lamp manufacture to form the solid adhesive from a liquid suspension of the polymerization reactants which do not contain volatile solvents. By employing such common adhesive binder, it becomes possible to employ an electrically-insulating basing cement for adhesively bonding the lamp envelope to the base shell along with an electrically-conducting basing cement for adhesively bonding the side lead to the base shell and to cure both basing cements simultaneously during high speed lamp manufacture in a single operation.

SUMMARY OF THE INVENTION

It is an important object of the invention, therefore, to provide an improved miniature size electric lamp construction having novel means to electrically connect the side lead wire to the inside surface of the lamp base shell.

Another important object of the invention is to provide a novel miniature size electric lamp construction wherein a common adhesive binder is employed to ad-

hesively bond the lamp envelope to the base shell and to adhesively bond the side lead to the inner rim of the base shell.

Still another important object of the invention is to provide a novel method of electrically connecting the side lead of an electric lamp to the metal base shell.

A still further object of the invention is to provide a novel method of basing an electric lamp wherein the lamp envelope and side-lead are adhesively bonded to the inner-surface of the base shell in a single heating operation.

Briefly stated, the present miniature size electric lamp construction includes a tungsten filament connected between a pair of wire leads which are hermetically sealed within a glass envelope, with said wire leads extending outwardly from said envelope and being electrically connected to a metal base shell wherein a portion of the side lead element is flattened and extends between the envelope wall and the rim of the base shell so as to lie in a plane approximately tangent to the envelope wall and being wedged between the wall of said envelope and the rim of said base shell and with said flattened portion of the wire lead also being adhesively bonded to the inside rim of the base shell with an electrically-conducting basing cement. In one of its preferred embodiments, said novel lamp construction further includes having the glass enveloped adhesively bonded to the inside wall of the base shell with an electrically-insulating basing cement utilizing the same adhesive bonding system employed in the electrically-conducting basing cement. In accordance with the general method of the present invention, the basing operation comprises the steps of flattening at least that section of the side lead which, in the final mounted position of the base on the lamp envelope end, will extend and intervene between the envelope wall and the rim of the base shell, the said flattening of said wire lead section being in a plane such that when the flattened section is in its said intervening position extending between the envelope wall and the rim of the base shell, it will lie in the plane approximately tangent to the envelope wall, applying a coating of an electrically-conducted basing cement to the flattened wire lead section, positioning the lamp base in its mounting position over the said end of the envelope with the said flattened wire lead section extending and wedged between the wall of said envelope and the rim of the metal shell of said base, and then heating the rim of the base shell and the said flattened wire lead section wedged between the base shell rim and the envelope wall to heat-cure the cement coating and adhesively bond said wire lead section to the inner-base shell.

Further objects and advantages of the invention will appear from the following detailed description of preferred embodiments thereof and from the accompanying drawing.

BRIEF DESCRIPTION OF THE DRAWING

In the drawing:

FIG. 1 is an elevational view showing the completed lamp construction having the side lead adhesively bonded to the inner-surface of the base shell rim and the lamp envelope adhesively bonded to the inside wall of the base shell below the rim; and

FIG. 2 is a cross-sectional view taken along the line 2-2 to show the disposition of the individual basing cements in the lamp construction of FIG. 1.

DESCRIPTION OF THE PREFERRED
EMBODIMENTS

Referring to the drawings, the invention is therein illustrated as applied to the manufacture of a subminiature electric incandescent lamp such as that commercially designated as the No. 327 type lamp customarily used for indicator and instrument lighting purposes. As shown in FIG. 1, said lamp comprises a sealed evacuated tubular glass bulb or envelope 1 of very small size, e.g., around 7/32 inch diameter and 1/2 inch or so in length which is closed off at its neck end 2 by the residue of an exhaust tube tip 3. Sealed into the envelope 1 is a lamp mount 4 comprising a filament 5, which may be in the form of a coiled tungsten wire, connected at its ends across a pair of spaced metal wire leads or lead-in wires 6 and 7 which are bridged and held in spaced relation by glass support bead 8 fusion sealed to the wires 6 and 7. As shown, the wire leads 6 and 7 are sealed through the side wall 9 of the envelope 1 at the neck end 2 thereof and at locations more or less diametrically opposite one another, by a conventional butt-type hermetic seal. A lamp base 10 comprising a metal shell 11 and a metal end contact eyelet 12 secured together by an insulator ring 13 is mounted on the neck end 2 of the envelope 1. The neck end 2 of the envelope 1 extends into the open end of, and is secured in place to the base shell 11 by a customary ring 14 of an electrically-insulating lamp basing cement. As shown, the base shell 11 is of slightly larger diameter, that is, around 1/32 inch or so larger diameter, than the outside diameter of the tubular glass envelope or bulb 1 so as to permit bulb end first insertion of the lamp into a lamp socket. The open inner end of the base shell 11 into which the envelope 1 extends is formed with an inwardly rolled or inturned curved lip or rim 15 within which the envelope 1 is snugly received to center it in place more or less axially of the base shell. One of the wire leads, e.g., wire lead 6, herein referred to as the side-lead, is electrically connected to the base shell 11 by adhesively bonding it thereto with a node or bead of an electrically conducting type basing cement 17, while the other or center wire lead 7 is soldered to the center or end contact eyelet 12 of the lamp base 10.

As more clearly seen in the cross-sectional view of FIG. 2, taken along the line 2-2 in FIG. 1, the ring of electrically-insulating cement 14 underlies the node or bead of electrically-conducting cement 17 in the lamp embodiment. The electrically-conducting cement does not extend around the inside periphery of the base shell in order to avoid contact with and short circuiting between the wire leads 6 and 7. In the final construction, therefore, the electrically-conducting cement overlies the electrically-insulating cement at the rim of the base shell, but is disposed adjacent only to the side-lead.

A particularly useful dual-purpose type basing cement which can be employed in the above described lamp construction is disclosed in the aforementioned pending application, Ser. No. 320,531. As therein disclosed, a basing cement composition utilizing as the adhesive binder the heat-cured product of a 1,2-butadiene prepolymer, a vinyl type crosslinker and a free-radical initiator can be employed which in one form provides an electrically non-conducting adhesive, but which can also be modified to provide an electrically-conducting adhesive for use in the lamp construc-

tion. Said in a different way, such basing cement composition provides a means of adhesively bonding one or more of the lead-in wires of the lamp along with the lamp envelope to the metal base shell to effect either 5 electrical isolation between the bonded lead-in wire or the lamp envelope and the base or to provide electrical connection therebetween. The alternative forms of these basing cements are compatible for lamp manufacture in that both can be employed for a single lamp 10 construction without significant intermixing which could further occasion short circuiting between the individual lead-in wires. Both forms of such type basing cement can be heat-cured simultaneously utilizing the same heating condition of heating in air for approximately 15 20 seconds at around 240°C which takes place during the automatic lamp manufacture. When an insulative type filler is admixed with the above specified liquid binder system, a heat-cured product is obtained providing electrical isolation and useful insulative fillers include titanium dioxide pigment or finely divided white glass which are non-alkaline so as not to inhibit heat-curing of the polymerization system. When an 25 electrically-conductive type filler is selected such as finely divided metal solids and the like, then a heat-cured product is obtained which conducts electrically so that a lead-in wire bonded with such cement would also be electrically connected to the metal base shell of the lamp. A typical composition for both type basing cements comprises 50-90 parts of a 1,2-butadiene prepolymer, 5-25 parts of a vinyl crosslinker, and 1-4 parts 30 of a free-radical initiator which further contains 200-300 parts of the filler. An especially effective composition for the electrically-conducting basing cement further utilizes as the conductive filler glass microspheres coated with a conductive metal along with up to 10 percent by weight of said microspheres being 35 finely divided conductive metal solids.

In mounting the base 10 on the lamp envelope 1 in the above described lamp embodiment and electrically connecting the side-lead 6 to the metal shell 11 of the base in a manner according to the invention, the outer end portion 6' of the lead wire 6 extending outwardly of the envelope wall 9 from its seal therethrough is first 40 formed on the lamp manufacturing equipment so as to extend in a substantially straight direction laterally outward from the envelope 1. The outer end portion 7' of the other or center contact wire lead 7 is also preferably formed to extend in a substantially straight direction laterally outward from the envelope 1 and angled 45 toward the tip end 3 thereof. At least a section 16 of the outer side-lead portion 6' adjacent its point of emergence from the lamp envelope 1 and which, in the final mounted position of the base 10 on the envelope end 2 will extend and intervene between the envelope wall 50 and the rim 15 of the base shell 11, is then flattened in a plane transverse to the axis of the envelope 1, by compressing it between a pair of opposed jaws on the lamp manufacturing equipment so that when the outer lead portion 6' is bent to extend alongside the side wall 55 of the envelope toward the end thereof opposite its neck end 2, the flattened section 16 will lie flatwise against and tangent to the envelope side wall. The flattened section 16 of the side outer lead portion 6' is then provided with a liquid coating of electrically-conducting basing cement as above described prior to 60 positioning the lamp base shell in its mounting position over said end of the lamp envelope for the assembly 65

therebetween. In this manner of assembly between the lamp envelope and the base shell, there will be no physical interference between the members being assembled. When the base 10 is thereafter placed in mounting position on the neck end 2 of the glass envelope 1, the envelope and the base 10 are then axially displaced away from one another to expose the flattened wire lead portion 16 of the bent side lead extending alongside the envelope wall, and said members are then moved axially together and repositioned relative to one another to again locate the base in its final mounting position on the neck end 2 of the envelope. When the base shell 11 is thus assembled in its mounting position with said lamp envelope 1, there is also present a ring 14 of liquid electrically-insulating type basing cement as above described which is peripherally disposed below the rim 15 of the base shell as shown in FIGS. 1 and 2.

While the envelope 1 in the base 10 are thus supported in their assembled position with the base end 10 positioned up, the rim 15 of the base shell 11 is suitably heated, as by means of gas fires directed thereagainst, to heat-cure the electrically-conducting basing cement on the flattened wire lead portion 16 and adhesively bond said portion between the base shell rim and the envelope side wall so as to effect electrical connection of said side lead to the base shell as shown in FIG. 1. The heating of the base shell to form said connection also simultaneously acts to cure the ring 14 of the electrically-insulating basing cement on the inside wall of the base shell so as to cause it to adhesively bond the side wall of the glass envelope in place on the neck end 2 of the envelope. With the electrical connection of the side lead 6 to the base shell 11 and the securing of the base 10 to the glass envelope 1 thus effected, the lamp basing operation can then be completed by trimming any excess portion of the side wire lead and exposed beyond the rim 15 of the base shell 11, as by breaking it off at the rim of the base shell, then trimming off the excess portion of the end contact wire lead 7' exposed beyond the end contact eyelet 12 of the base 10 after said wire lead 7 has been soldered to the eyelet in a manner customary in a lamp-manufacturing art.

It will be apparent to those skilled in the art from the foregoing description that a novel lamp construction has been disclosed along with a novel method of providing said lamp construction. It will also be appreciated that various changes can be made in said lamp construction and method without departing from the spirit and scope of the invention. For example, it is contemplated that said lamp construction and method could further include additional pretreating of the side-

lead element before adhesive bonding to the base shell, such as by cleaning or by depositing an electrically-conducting coating thereon to further improve the electrical connection. Likewise, such pretreated side-lead could also be employed without modification of the method herein disclosed. It is therefore intended to limit the present invention only by the scope of the following claims.

What we claim is new and desire to secure by Letters 10 Patent of the United States is:

1. In a miniature size electric lamp having an tungsten filament connected between a pair of wire leads which are hermetically sealed within a tubular shaped glass envelope, with said wire leads extending outwardly from said envelope and being electrically connected to a cylindrical metal base shell having an in-turned rim, the improvement which comprises having one flattened wire lead extending between the envelope wall and the rim of the base shell so as to lie in a plane approximately tangent to the envelope wall and being disposed between the wall of said envelope and the rim of said base shell, said wire lead being adhesively bonded to the inside rim of the base shell with an electrically-conducting base cement utilizing a heat cured organic polymer binder having a finely divided conductive solid dispersed therein.
2. An electric lamp as in claim 1 which further includes having the glass envelope adhesively bonded to the inside wall of the base shell with an electrically-insulating basing cement.
3. An electric lamp as in claim 2 wherein the electrically-insulating basing cement is peripherally disposed in a ring around the inside wall of the base shell below the rim and the electrically-conducting basing cement overlies the electrically-insulating basing cement at the rim of the base shell but is disposed adjacent only to one wire lead.
4. An electric lamp as in claim 1 wherein the basing cement comprises the heat-cured product of a 1, 2-butadiene prepolymer, a vinyl-type crosslinker, and a free-radical initiator which further contains a filler of conductive metal particulates.
5. An electric lamp as in claim 4 wherein the conductive metal particulates comprise glass microspheres coated with a conductive metal.
6. An electric lamp as in claim 2 wherein the electrically-insulating basing cement comprises the heat-cured product of a 1,2-butadiene prepolymer, a vinyl type crosslinker, and a free-radical initiator.
7. An electric lamp as in claim 6 which further contains a filler of electrically-insulating particulates.
